Application May 11, 1954, Serial No. 429,068

Claims priority, application Germany May 13, 1953

8 Claims. (Cl. 112—228)

The invention relates to sewing machines, and relates more particularly to sewing machines of the double stitch type; still more particularly, the invention relates to a rotatable hook for double stitching sewing machines that defines a guide way for the external rib of a fixed bobbin case. More particularly still the invention relates to a bow for use in connection with such a hook, and means for maintaining said bow on said hook in active position.

Hooks of this type normally are formed of a hub and a body that includes a pointed end for engaging the loop of the upper thread. On the interior of the hook there is formed a guide way that comprises in part an annular groove and a cutaway portion in which there is journaled the external rib of the bobbin case. The cutaway portion is normally covered by a hook bow.

In accordance with the previous constructions, the hook bow is attached to the hook by screw elements. By loosening the bow, there is released about one half of the guide way, to remove the bobbin case for cleaning the interior of the hook. In embodiments of the prior art, the bow is either formed as a flat bow or as an angular bow having a rectangular cross section. The use of a flat bow requires the use of screws that are mounted parallel to the axis of the hook. This admits none but screws of minute dimensions, unless the diameter of the entire hook is greatly increased.

The angular bow, on the other hand, is held with screws perpendicular to the axis of the hook, and thus permits the use of screws of sufficiently large size. It provides, however, the drawback that the body of the hook may be deformed during tightening of these screws, which renders such hook incapable of interchange.

In both of the aforementioned constructions of the prior art, there is found the deficiency that they are connected by means of several screws with attendant loss of time during mounting and dismounting of the bow on the hook.

It is among the principal objects of the invention to provide a hook and bow in which the aforesaid disadvantages are obviated. Broadly speaking, the construction provides for a bow that for a major portion of its length is formed as a flattened bow and which is so formed at its longitudinal ends that it covers the guide way and the wall of the hook body in the manner of an angular bow.

With the above and other objects of the invention in view, the invention consists in the novel constructions, arrangement and combination of various devices, elements and parts, as set forth in the claims hereof, certain embodiments of the same being illustrated in the accompanying drawings and described in the specification.

In the accompanying drawings there are shown perspective views illustrating in:

Fig. 1 in extended form, a bow in accordance with one embodiment of the invention;

Fig. 2 a spring for use with the embodiment of Fig. 1;

Fig. 3 a hook for use in connection with the bow of Fig. 1 and the spring of Fig. 2;

Fig. 4 a hook of the type shown in Fig. 3 on which there are attached the bow of Fig. 1 and the spring of Fig. 2;

Fig. 5 a modified bow seen from the interior;

Fig. 6 the bow of Fig. 5 but seen from the exterior;

Fig. 7 a hook body for use with the bow shown in Figs. 5 and 6;

Fig. 8 a still further modified bow seen from the interior;

Fig. 9 the bow of Fig. 8 but seen from the exterior; and Fig. 10 a hook body for use with the bow of Figs. 8 and 9.

In carrying the invention into effect the embodiments which have been selected for illustration in the accompanying drawings and for description in this specification and referring now particularly to Figs. 1-4 there is provided a hook that includes a hub 1 and a body 2 which includes a point 3. On the interior of the body 2 there is provided a guide way 4 that is formed as an arcuate recess, in one part as a groove adjacent an integral ridge (Fig. 3) and for the remainder as a cutaway portion 5. The cutaway portion 5 is covered by a bow 6 which forms a ridge for the recess, and a hinge 7 is provided between the body 2 and the bow 6. A pin 7' forms part of the hinge 7.

An angular part 8 of the bow 6 is provided near one end thereof, and forms the trailing end for the thread loop. The bow 6 furthermore comprises a lug 9 that has a surface 10 that is parallel with the guide way 4 and has an abutment surface 11 for a leaf spring 12 (Figs. 1, 2, and 4). Said spring 12 is connected to the body 2 by means of screws 13 and 14 that are threaded in screw holes 13" and 14" formed in the wall 15 of the body 2. A rib 16 extends interiorly on the periphery of the top of the wall 15. The spring 12 has counter-sunk openings 13' and 14' for the passage of the screws 13 and 14.

As best shown in Fig. 4, the bow 6 is hinged with the hinge 7 to the body 2, and its surface 10 of the lug 9 engages the under-surface of the rib 16, while the spring 12 presses against the surface 11 to maintain resiliently the bow 6 in the active position in which it covers the cutaway portion 5 of the guide way 4. The bow 6 may be moved away from the active position against the power of the spring 12 to permit removal of the bobbin case off the guide way 4 and out of the hook for cleaning of the hook interior.

The spring 12 is so dimensioned that its active radius is smaller than the radius of the surface 11 about the axis of the hinge pin 7', so that the spring 12 will release the bow 6 following a short outward movement of the bow 6.

In the active position (Fig. 4) the surface 10 engages the rib 16, which engagement is rendered ineffective when the bow 6 is moved away from the active position.

In the modification, shown in Figs. 5-7, the cutaway portion 5 of the guide way 4 of the body 2 is covered by a bow 17. The bow 17 has at its front end a flat member 18 and an extension 19 at right angle to the longitudinal direction of the bow 17. The extension 19 has two lateral surfaces that are radially of the axis of the hook. On the rear end of the bow 17 there is provided an angular piece 22 that has a counter-sunk hole 23 and that has an oblique lateral surface 24. A recess 28 is provided in the wall 25 of the body 2 matching the shape of the extension 19. The wall 25 furthermore has a recess 26 that matches the shape of the piece 22, and includes an oblique surface 27 that matches the surface 24. A depression 29 is provided on top of the wall 25 to receive the member 18.

A screw 23 engages the threaded bore 23" and passes through the bore 23'. The extension 19 and recess 28, and the piece 22 of the recess 26, are so arranged that

the bow 17 in the active position is restrained in movement in all but one direction, and the screw 23 restrains movement in that one direction.

In the modification shown in Figs. 8-10, there is provided a bow 30 that has at the rearward end a piece 30' similar to the piece 22 of the modification of Figs. 5-7, and has at the forward end an extension 31 perpendicular to the longitudinal direction of the flat portion of the bow 30. The flat portion has a lower surface 34 (Figs. 8 and 9) for abutment against the top surface of the wall 37 of the body 2. The extension 31 has an oblique side surface 35 and an opposite surface 32 that is radial of the axis of the hook, and has an inner surface 33. A recess 36 is provided in the wall 37, and the recess 36 has a shape corresponding to that of the extension 31 including an oblique lateral surface corresponding to the surface 35. The wall 37 has a bore 38" for a screw 38 that passes through a counter-sunk hole 38' that is formed in the piece 30'.

The oblique surface 35 is so arranged that the extension 31 widens towards the bottom of the body 2. The extension 31 and the piece 30' and the recess 36 for the extension 31 of the opposite recess for the piece 30' are so arranged that there is a forced engagement between the bow 30 and the body 2 save for movement in one direction which is restrained by the screws 38.

It will be apparent to those skilled in the art that the novel principles of the invention disclosed herein in connection with specific exemplifications thereof will suggest various other modifications and application of the same. It is accordingly desired that in construing the breadth of the appended claims they shall not be limited to the specific exemplifications of the invention described herein.

Having thus described the invention, what we claim as new and desire to be secured by Letters Patent, is as follows:

1. In a revoluble hook, for use in connection with a double stitching sewing machine, in combination, an arcuate walled body having an internal arcuate recess forming a guideway and including an integral first ridge alongside a portion of said recess, said walled body being cut away forming an edge near another portion of said recess, and an elongated hook bow removably connected to said body, said hook bow comprising an arc shaped part flattened in a plane perpendicular to the arc and having extensions near the opposite ends, said flattened part of said hook bow defining a flange projecting inwardly over said edge into the interior of said walled body and forming a second ridge along said other portion of said recess disposed substantially diametrically opposite said first ridge, said extensions engaging externally said walled body.

2. In a hook as claimed in claim 1, together with, hinge means between said body and said hook bow removably connecting said bow to said body, said bow being movable about the axis of said hinge means to and from an active covering position on said body, and

resilient means removably secured to said body pressuring said bow resiliently into said active position.

3. In a hook as claimed in claim 1, together with, means between said bow and said body releasably engaging said bow on said body restricting movement of said bow in all but one direction, and means operable for resisting movement of said hook in said one direction.

4. In a hook as claimed in claim 1, said body having external recesses operable each corresponding to the outline and configuration of an extension for receiving the same, whereby said bow will be engaged on said body immovably in all directions but one, and means restraining movement in said one direction.

5. In a hook as claimed in claim 1, one of said extensions of said hook bow being perpendicular to the longitudinal direction thereof, and the other extension having side surfaces disposed radially of the axis of said body, corresponding recesses formed in said body for receiving said extensions in abutment, said extensions and recesses forming means positioning said hook bow in an active covering position on said body immovably in all but one direction, and a screw restraining movement of said hook bow in said one direction completing the removable attachment of said hook bow to said body.

6. In a hook as claimed in claim 1, one of said extensions of said hook bow being perpendicular to the longitudinal direction thereof, and the other extension having side surfaces disposed radially of the axis of said body, corresponding recesses formed in said body for receiving said extensions in abutment, said extensions and recesses forming means positioning said hook bow in an active covering position on said body immovably in all but one direction, and a screw restraining movement of said hook bow in said one direction completing the removable attachment of said hook bow to said body, one of said side surfaces being oblique relative to the longitudinal direction of said flattened portion, and the corresponding recess having a matching inclined surface for abutment with said oblique surface.

7. In a hook as claimed in claim 1, said hook bow being hinged to said body, a leaf spring pressing said bow, abutment means intermediate said body and said bow defining an active covering position of said bow, and resilient means pressing said body into said active position.

8. In a hook as claimed in claim 7, said resilient means including a spring having an active radius smaller than the distance of said abutment means from the hinge axis.
